HAIR PERMANENT WAVING APPARATUS

Filed July 26, 1928

UNITED STATES PATENT OFFICE

HARRY BONAT, OF NEW YORK, N. Y.

HAIR-PERMANENT-WAVING APPARATUS

Application filed July 26, 1928. Serial No. 295,429.

- This invention relates to apparatus for use in connection with hair permanent waving and more particularly to apparatus for holding the hair in a fixed position during the permanent waving treatment.
- An object of the invention is to provide new, simple, efficient and inexpensive apparatus for use in connection with hair permanent waving.
- 10 Various devices have been in use heretofore for holding hair in the desired position during the permanent waving treatment but all of said devices have been found to be unsatisfactory. In some of the apparatus used 15 the protector which rests closely against the scalp of the patient has been of such thickness as to prevent the hair close to the scalp from being waved and moreover the material of which the protector has been composed 20 was such as to transmit some heat to the scalp thereby causing discomfort. Moreover, in some of the arrangements heretofore used the spool on which the hair was wound was so secured to the protector during the 25 application of heat that it became necessary to move the spool such a considerable distance longitudinally upon the completion of the treatment for unwinding the hair that further discomfort was inflicted upon the patient.
- According to the present invention the difficulties found in the devices commonly used have been overcome by providing a protector of such material as to permit the same to be 30 made relatively thin and at the same time to prevent the transmission of heat to the scalp of the patient. The material of which the protector is principally composed is such as to form a good heat insulating material and 35 the protector is so constructed as to permit the hair close to the scalp to become waved as well as that remote therefrom. In order that the hair may be removed after the treatment without causing strain thereupon the 40 present invention provides a spool used in conjunction with the protector, provision being made that the spool may be disengaged from the protector with a minimum of longitudinal movement.
- 45 Other objects and features of the present invention will become apparent by reference to the following detailed description read in the light of the accompanying drawing, wherein—
- Figure 1 is a perspective view of a protector spool embodying my invention shown in operative position; 55
- Figure 2 is a perspective view of a protector composing an embodiment of the invention in unlocked position; 60
- Figure 3 is a perspective view of a preferred form of spool of the invention; 65
- Figure 4 is a side view of the protector and the spool illustrated in Figs. 2 and 3, such spool and protector being in normal operative position;
- Figure 5 is a view partly in section of one end of the structure illustrated in Fig. 4; 70
- Figure 6 is a view of the other end thereof;
- Figure 7 is a view similar to Fig. 4 of a modified embodiment of the invention; 75
- Figure 8 is an end view partially in section of the arrangement illustrated in Fig. 7; and
- Figure 9 is an enlarged view of a portion of the arrangement illustrated in Figs. 7 and 8.
- Referring now to the drawings, 10 indicates a protector for use in connection with hair permanent waving upon which and to which is secured in a manner hereinafter to be explained a spool 11 upon which the hair is wound. The protector 10 is composed of a pair of relatively thin strips 12 and 13 of suitable heat insulating material which are joined together at one end by means of a cross bar 14 which is rigidly secured to the strip 12 and pivotally secured to the strip 13 thereby permitting the strips to be moved pivotally with respect to each other. The heat insulating material is preferably Bakelite but it is to be understood that any other material having suitable properties may be used efficiently. The strips 12 and 13 are provided at one end with slots 15 and 18 respectively. 80
- In the slot 15 of strip 12 is pivotally mounted a bar 16 to the end of which is a cam-like latch member 17. The bar 16 is adapted to pass through the slot 18 in the end of strip 13 85

and to be locked in position by means of the latch member 17 as shown more clearly in Fig. 4. In order that the protector when resting upon the head of the patient may cause no irritation due to the hardness of the surface thereof a thin strip of felt 19 is affixed to the bottom of each of the strips 12 and 13. Since the hair to be treated must be wound tightly it becomes necessary to provide means for preventing such strain thereupon as would cause discomfort to the patient. For this purpose the inner edge of each of the strips 12 and 13 is provided with a strip of resilient material 20, such as rubber or other suitable preparations. It would become evident from this that by this arrangement the hair held between the respective strips of rubber or other suitable resilient material 20 will be so held as to prevent the pull exerted upon the hair from being transmitted to the scalp of the patient.

In hair permanent waving the hair must be wound around some substantially cylindrical object to form the desired waves. In the present invention use is made of a spool 21 the body of which is of conventional design and structure and has affixed thereto a catch 22 which tends to hold the hair firmly against the body of the spindle when the same is wrapped therearound. Inasmuch as the hair wrapped around the spindle 21 must not be permitted to slip therefrom during the heat treatment, means is provided for holding the spindle against the pad 10 free from rotation or movement other than longitudinal. For this purpose a metallic standard 23 is affixed to the strip 12, such standard having a vertical portion 24 extending in such manner that when the two strips 12 and 13 are in locked position the standard 23 is in substantially the center of the pad. The standard 23 is insulated from strip 12 by means of a layer 40 of asbestos, and a similar layer 41 of asbestos insulates plate 23' secured to strip 13 from such strip. The portion 24 is provided with a hole 25 in the approximate center thereof, such hole lying substantially over the mid-point of the joined strips 12 and 13. Extending inwardly from the side of standard 23 is a pawl 26 formed from a portion of the standard 23 such portion being punched therefrom. To the other end of the strip 12 is secured a plate 27. A layer 42 of asbestos serves as a heat insulation between plate 27 and strip 12, while a layer 43 of asbestos, secured to plate 27, serves as insulation between the plate and strip 13. Affixed to the top of member 27 is an upstanding substantially U-shaped member 28 for receiving and holding in place one end of a spool 21.

The spool 21 is provided at one end with an enlarged shoulder 30 the end of which is toothed as shown at 31 to form ratchet teeth for engagement with the projection 26 which acts as a pawl for such teeth. Extend-

ing from the center of the end of the shoulder 30 is a short pin 32 adapted to fit within the hole 25 in standard 23.

The operation of the apparatus previously described is as follows: The strand of hair to be waved is placed between the strips 12 and 13, such strips being positioned directly upon the scalp of the patient. The strips are then locked by means of the bar 16 and latch 17 thereby firmly holding the strands of hair between the resilient members 20 on the inner faces of these strips. The hair is then wrapped around the spool 21, which as shown has a varying diameter tapering from the minimum at the center thereof to the maximum near the ends thereof, such tapering arrangement permitting the hair to be wrapped around the spool and upon completion of the wrapping to lie substantially flat as illustrated more clearly in Fig. 1. Due to the catch 22 the hair when wrapped around the spool will not ordinarily slip from the spool but it is necessary that the hair should not unroll during the heat treatment. Accordingly as the hair becomes wrapped around the spool close to the pad 10 the pin 32 is inserted in the opening 25 and rotation continued. As this rotation continues the ratchet teeth 31 engage successively the pawl 26 and due to the tension on the hair when the spool is rotated as much as possible by means of a wrench or other suitable tool engaging projections 33 on the end of the spindle the pawl 26 in connection with one of the teeth 31 will prevent the spool from rotating and will not permit any movement of the spindle other than longitudinal. In this position the end of the spindle 21 opposite from shoulder 30 rests in and is supported by the substantially U-shaped member 28. After the heat treatment is completed it becomes necessary to move the spool 21 a slight distance longitudinally, such distance being merely sufficient to permit the disengagement of pin 32 from opening 25 after which the hair may be unwound from the spool.

From the foregoing it will be seen that due to the thinness of the protector 10 the hair may be waved very closely to the scalp and at the same time the thinness of the protector does not permit transmission of heat to the scalp of the patient due to the fact that the strips forming the protector are of heat insulating material and also that a minimum number of metallic parts are utilized. Moreover the provision of the layers 40, 41, 42 and 43 of asbestos hereinbefore described serve to prevent transmission of heat from standard 23, plate 23' and plate 27, with which the spool contacts, to the strips 12 and 13 and thence to the scalp of the patient.

The modified embodiment illustrated in Figs. 7, 8 and 9 consists of a protector 10' composed of parts similar to those composing protector 10 with the exception that a differ-

ent type of standard is utilized in the place of the standard 23 of pad 10 and likewise that the end of the shoulder 30' is somewhat different from the end of shoulder 30. Similar parts are given similar numbers with the addition of a prime to each numeral. In this modification the standard 23' is provided with a pawl 26' similar to pawl 26 but in place of the opening 25 the standard is provided with an annular flange or rim 35 which extends substantially entirely around the standard. Furthermore, the spindle 21' is provided with ratchet teeth 31' but is not provided with a pin similar to pin 32.

In the operation of the modification just described the hair is affixed between the edges of the strips of the protector as before and the hair wrapped around the spindle 21' in the same manner as previously described. Upon the completion of the winding the spindle 21' will be held against rotation in the same manner as previously described and will be held against any movement other than longitudinal by reason of the annular flange 35 which serves the same purpose as the pin 32 and opening 25.

From the foregoing it will be seen that the present invention provides an improved apparatus for the purpose set forth. By providing a pawl member punched from and forming an integral part of the standard, a more durable and simpler structure is obtained. The invention is not to be limited to the illustrated embodiments but only by the scope of the appended claims.

I claim.

1. Apparatus of the character described comprising a protector composed of thin strips of heat-resisting material joined in pivotal relation, a standard extending perpendicularly from said protector and having a pawl member punched therefrom, and a spool having ratchet teeth on one end thereof extending radially outwardly from near the axis of the spool, said ratchet teeth being adapted for engagement with said pawl member.

2. Apparatus of the character described comprising a protector composed of thin strips of heat-resisting material joined in pivotal relation, a standard extending perpendicularly from one end of said protector and having a pawl member punched therefrom, a spool support at the other end thereof, strips of heat-resisting material interposed between the strips of said protector and said standard and said support, and a spool having ratchet teeth on one end thereof extending radially outwardly from near the axis of the spool, said ratchet teeth being adapted for engagement with said pawl member.

3. Apparatus of the character described comprising a protector composed of thin strips of heat-resisting material joined in pivotal relation, a stationary standard extending

perpendicularly from said protector and having a pawl member punched therefrom and extending at substantially right angles thereto, said standard being provided with a centrally located opening, and a spool having ratchet teeth adapted for engagement with said pawl member, said spool being provided with a pin for engagement with said opening.

4. Apparatus of the character described comprising a protector composed of thin strips of heat-insulating material joined in pivotal relation, a spool around which hair may be wrapped, a pin extending from one end of said spool and ratchet teeth on the end of said spool and extending radially outwardly substantially from said pin, an upright standard on said protector having a portion cut away for the reception of said pin, and a pawl member extending inwardly from said standard for engagement with said ratchet teeth.

5. Apparatus of the character described comprising a protector composed of thin strips of heat insulating material joined in pivotal relation, a spool around which hair may be wrapped, a pin extending from one end of said spool, a stationary upright standard on said protector having a portion cut away to provide a seat for said pin, a pawl member formed as a part of said standard and ratchet teeth on said spool for engagement with said pawl.

In testimony whereof, I have signed my name to this specification.

CERTIFICATE OF CORRECTION.

Patent No. 1,756,451.

Granted April 29, 1930, to

HARRY BONAT.

It is hereby certified that error appears in the printed specification of the above numbered patent requiring correction as follows: Page 1, line 56, before the word "spool" insert the word "and"; page 2, line 15, for the misspelled word "prepartions" read "preparations", and line 50, after the word "formed" insert "preferably but not necessarily"; and that the said Letters Patent should be read with these corrections therein that the same may conform to the record of the case in the Patent Office.

Signed and sealed this 24th day of June, A. D. 1930.

(Seal)

M. J. Moore,
Acting Commissioner of Patents.
